UNITED STATES PATENT OFFICE.

SOPHIA M. OBERLANDER, OF BALTIMORE, MARYLAND.

RUBBER BOOT.

SPECIFICATION forming part of Letters Patent No. 288,846, dated November 20, 1883.

Application filed September 22, 1883. (No model.)

To all whom it may concern:

Be it known that I, SOPHIA M. OBERLANDER, a citizen of the United States, residing at Baltimore, State of Maryland, have invented 5 certain new and useful Improvements in Rubber Boots, of which the following is a specification.

My invention relates to an improvement in rubber boots, the object being to provide a 10 boot suited for ladies' wear which shall have a water-proof foot and a high leg of internal capacity for the largest person, and at the same time provision to cause the upper part of the boot-leg to fit close about the leg of a 15 person.

In the drawings hereto annexed, Figure 1 is a view of the boot as seen when the flap is buttoned. Fig. 2 is a view showing the flap open and exposing the lacing. Fig. 3 is a top view 20 of the boot-leg. Fig. 4 is a front view of the boot-leg.

The letter A designates the water-proof foot of an ordinary rubber boot; B, a high leg attached to the foot. The leg has a flap, c, one 25 of the vertical sides of which is integral with or permanently attached to the side of the boot-leg, from which point the flap extends across the front of the leg, and its free vertical side opens from the top of the leg downward to a point near or just above the instep. Near the edge of the free side of the flap are holes d, and the leg has on the outer side a row 30 of buttons, e, thereby providing for fastening the flap. The boot-leg and flap are composed of 35 rubber. The front of the leg, which the flap covers, has inside of the flap two face-pieces, f, each having a straight vertical edge, f', which two together form a center slit from the top of the boot-leg to a point above the lower part 40 of the flap, whereby, when the flap is fastened,

the said slit and face-pieces will be completely covered. The face-pieces may be composed of any suitable material, not necessarily of rubber. Each side of the face has a row of lacing-holes, g, and an ordinary shoe string or 45 lace, h, is employed to draw the two pieces of the face together, as shown in Figs. 2 and 4, whereby the top of the boot-leg may be made to clasp the leg of the person, while if the boot-leg be too large the flap may stand off 50 therefrom. This boot may be readily drawn on the foot, and then the front slit is laced to cause the upper part of the boot-leg to fit close about the leg of the wearer. Then the flap is brought over the lacing and buttoned. Thereby the boot is comfortable about the leg, a neat 55 appearance is produced, and water is excluded.

I am aware that in the manufacture of boots and shoes a buttoned flap has been employed to cover a laced slit, and such, therefore, I do 60 not claim, broadly.

Having described my invention, I claim and desire to secure by Letters Patent of the United States—

A rubber boot having a water-proof foot, 65 A, and a high leg, B, which latter is provided at the front with a center vertical slit extending from the top to a point above the instep and closed by a lace, and a rubber flap, c, having one of its vertical sides permanently attached to the side of the boot-leg, and its free side adapted to cover the vertical slit and lacing, and fastened by buttons only to the outer side of the boot-leg, as set forth.

In testimony whereof I affix my signature in 75 presence of two witnesses.

SOPHIA M. OBERLANDER.
